UNITED STATES PATENT OFFICE.

CHARLES HENRY FRENCH, OF CANTON, MASSACHUSETTS, ASSIGNOR TO FRENCH & WARD, OF NEW YORK, N. Y., A FIRM.

DESIGN FOR A KNIT FABRIC.

No. 38,209.

Specification for Design.

Patented Aug. 28, 1906.

Application filed July 31, 1906. Serial No. 328,636. Term of patent 7 years.

To all whom it may concern:

Be it known that I, CHARLES HENRY FRENCH, a citizen of the United States, and a resident of Canton, in the county of Norfolk and State of Massachusetts, have invented a new, original, and ornamental Design for a Knit Fabric, reference being had to the accompanying drawing, in which the figure is a plan view of a knit fabric, showing my design.

I claim—

The ornamental design for a knit fabric as shown.

CHARLES HENRY FRENCH.
